(57) **CLAIM**

The ornamental design for a weightlifting attachment, as shown and described.

DESCRIPTION

FIG. 1 is a top, front, right perspective view of a weightlifting attachment showing my new design;

FIG. 2 is a bottom, front, left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a top, front, right perspective view thereof, shown with a portion of a weight rack as example environment. The broken lines in the drawings depicting the remainder of the article show features that form no part of the claimed design. The additional broken lines in FIG. 9 illustrate example environment that forms no part of the claimed design.

1 Claim, 9 Drawing Sheets
